METHOD OF TRUING AND DRESSING AN ABRASIVE WHEEL AND APPARATUS THEREFOR
William B. Seidel, Cincinnati, Ohio, assignor to The Cincinnati Milling Machine Co., Cincinnati, Ohio, a corporation of Ohio

Filed Apr. 6, 1960, Ser. No. 20,392
10 Claims. (Cl. 125—11)

The present invention relates to a method of truing and dressing an abrasive wheel, and mechanism therefor.

In conventional diamond truing or dressing of an abrasive wheel, a diamond is fixed in a holder which is moved across a surface of the rotating wheel with the diamond in engagement therewith. The diamond is held at a trailing angle relative to the surface of the wheel, and a facet is worn on the diamond. In most operations, as, for example, dressing the periphery of a cylindrical wheel, this facet is very nearly flat and as the diamond wears, the area of the facet, or flat, increases, increasing the area of contact between the diamond and the wheel. The increased friction between the diamond and the wheel produces more heat and promotes more rapid wear of the diamond. As the area of the flat in contact with the rotating wheel increases, fewer grains are fractured and flat surfaces are produced on many of the grains. Thus, the dressing, or sharpening, action of the diamond on the wheel progressively deteriorates.

The truing, or shaping, action of the diamond on the wheel is also impaired in many conventional truing operations as the diamond wears. For example, in truing an arcuate contour on a wheel with a tool traversing the wheel in translation under control of a cam, reproduction of the cam conformation on the wheel becomes less precise as the span of the contact area of the diamond increases in the traversing direction. As the span of the contact area increases, more widely spaced regions of that area will engage the wheel at different portions of the contour as the diamond moves transversely across the wheel and, although the diamond moves in conformity with the cam contour, the surface contoured on the wheel will not be a precise reproduction of the contour on the cam because different, transversely spaced, portions of the diamond have formed, respectively, different portions of the wheel. Moreover, it is known that a diamond offers a varying resistance to wear depending on the orientation of the crystal structure thereof relative to the direction of the abrading force, as described, for example, in U.S. Patent 2,889,822. In many contour truing operations different regions of the diamond are presented, at different orientations, to two or more portions of the contour and the attrition rate of the diamond will differ in the two regions of the diamond, making precision truing even more difficult.

In order to reduce the deleterious effects caused by the wear of the diamond it has been customary periodically to index the diamond holder between operations on the wheel. In this manner the facet previously worn thereon is rotated an incremental amount relative to the rotating wheel and a new facet is gradually formed on the diamond. The diamond again progressively deteriorates in its dressing and truing action on the wheel as the area of contact between the new facet and the wheel progressively increases.

There is provided in the present invention a method, and apparatus, whereby progressive loss of effectiveness of dressing and truing is eliminated. In brief, in the preferred form of the invention, a conical shaped diamond point is used. The diamond is oriented so that the cone defining the point establishes substantially line contact with the wheel. The diamond is rotated about a central axis through the apex of the cone as it is moved across the

2

face of the wheel so that no flat is worn on the diamond, and the shape of the diamond point, as well as the area of contact between the diamond and the wheel, remains substantially unchanged.

5 In the diamond point, instead of excessive heat being generated in one localized region which is in continuous contact with the wheel, as in conventional diamond truing, the heat generated by the contact between the tool and the wheel is distributed evenly over a substantially larger surface than the area in contact with the wheel. Since each region of the diamond point is in contact with the wheel only a small fraction of each revolution of the diamond, and is exposed to air or coolant for the remainder of each revolution, the heat generated in any region of the diamond point by contact with the wheel is continuously dissipated during the operation. With the heat generated by the action of the diamond on the wheel distributed over the entire diamond point and effectively dissipated continuously during the operation, wear of the diamond is reduced.

10 In the present invention where the diamond is rotated continuously during operation on the wheel, uneven wear caused by the irregular resistance to wear of the diamond is minimized. When a "soft" region of the conical surface begins to wear more rapidly than a "hard" region thereof, the "hard" region begins to bear a greater portion of the diamond action on the wheel, and thus wear on the "soft" region is automatically reduced. This automatic compensation tends to maintain the conical shape of the diamond. When the diamond is oriented so that the line contact between the diamond and the wheel is parallel to the direction of movement of the wheel at the diamond and thus perpendicular to the direction of traversing of the diamond across the wheel, the span of the substantially line contact between the conical diamond and the wheel in the traversing direction is minute, permitting much more precise truing in operations where the diamond is moved in translation across a contoured wheel.

15 Another advantage (and one more difficult to understand) stems from continuous rotation of the diamond while in engagement with the rotating wheel. It has been found that with a rotating diamond a wheel is produced which is substantially sharper, capable of many more grinds per dress, than would be expected from a wheel dressed with a diamond in the conventional manner. The precise action of the rotating diamond on the wheel is not fully understood but it is believed that the rotation of the diamond produces an additional force on the grains of the wheel which, when coupled with the fact that the diamond acts on a small (and unchanging) area of the wheel by virtue of the substantially line contact therebetween, consistently produces a higher unit load on the grains of the wheel to promote fracture thereof, without the formation of numerous flat surfaced grains and the diminution of effectiveness of dressing typical of conventional diamond dressing.

20 It is therefore one object of the present invention to provide an improved dressing method, and apparatus therefor, to produce a sharp grinding wheel. It is another object of the present invention to provide an improved dressing method, and apparatus therefor, to fracture the grains of a grinding wheel in a manner to produce sharp pointed grains. It is still another object to provide an improved grinding wheel truing method, and apparatus, which maintains the shape of the truing tool. It is another object of the present invention to provide an improved truing and dressing method by which heat is dissipated from the tool. It is still another object to provide a truing and dressing method, and apparatus therefor, in which wear of the tool is minimized. Other objects and advantages of the present invention should be readily apparent by reference to the following spec-

ification, considered in conjunction with the accompanying drawings forming a part thereof, and it is to be understood that any modifications may be made in the exact details there shown and described, within the scope of the appended claims, without departing from or exceeding the spirit of the invention.

In the drawings:

FIG. 1 shows a view, in perspective, of the diamond tool engaged with the peripheral face of a cylindrical grinding wheel, with part of the diamond tool housing cut away for clarity;

FIG. 2 shows a greatly enlarged side elevation view of the diamond point engaged with the peripheral face of the grinding wheel of FIG. 1;

FIG. 3 is a view taken on line 3—3 of FIG. 2;

FIG. 4 is a view taken on line 4—4 of FIG. 2;

FIG. 5 shows the diamond tool, in two different positions, as it moves across a contoured wheel; and

FIG. 6 is a view taken on the line 6—6 of FIG. 5 showing mechanism to move the tool across the wheel, the tool being shown in its extreme right hand position.

There is shown in FIG. 1, a dressing and truing tool, indicated generally at 10, having a spindle 11, with a longitudinal central axis 12, the spindle having a diamond nib 13 mounted at one end. As shown in FIG. 2 a diamond 14 is mounted in the nib on the axis 12. As in truing with a nonrotating diamond, axis 12 of the diamond tool is inclined relative to the face of the abrasive wheel to be trued, or dressed, as, for example, the peripheral face 15 of the grinding wheel 16.

The spindle 11 may be operatively connected to an electric or hydraulic motor for rotation thereby, but in the illustrative embodiment of the invention disclosed herein, there is provided a simple, compact drive, capable of high speed, to rotate the spindle. With higher speeds of rotation of the diamond during dressing, a better finish can be ground on a workpiece by the grinding wheel, because the effect on the grinding wheel of any slight irregularity of the diamond, or eccentricity of rotation thereof, decreases as the speed of rotation of the diamond increases. If, for example, one portion of the diamond is not completely effective in its action on the wheel, the diamond will be moved a smaller distance across the wheel while this less effective portion of the diamond is in contact with the wheel at higher angular speeds of the diamond. In operations where good finish on the workpiece is important, it is desirable to rotate the diamond at least at the angular speed of the grinding wheel and preferably faster. As shown in FIG. 1, the spindle 11 is mounted in a housing 17 by anti-friction bearings 18, 19, and 20. Turbine blades 21 connected to and radially extending from the spindle are received in a cylindrical chamber 22 in the housing. Chamber 22 has tangentially oriented ports (not shown) circumferentially spaced apart and connecting, respectively, to an air inlet passage 23 and a discharge passage (not shown). Fluid, such as air, under pressure is circulated through the housing and chamber 22 to rotate the turbine blades, and hence, the spindle and diamond.

The diamond 14 has a base portion 24 secured in the nib 13 by conventional means, and an extending shank 25 on axis 12. Since the axis 12 is inclined relative to the peripheral face 15 which is to be operated on, rotation of the spindle 11 about the axis 12 with the extending shank 25 of the diamond in contact with the wheel will generate a surface of revolution on the diamond, the conformation of said surface being determined by the profile of the wheel and the angle of inclination of the axis 12 relative to the wheel, and the diamond and the wheel will be engaged in substantially line contact. The axis 12 should be inclined at a trailing angle relative to the direction of travel of the surface 15 (that is, as shown in FIG. 1, inclined away from the direction of travel indicated by arrow A, of the surface 15 where it contacts the diamond relative to a line 26 from the

5 diamond through the axis (not shown) of the wheel). Preferably, the axis 12 is inclined so that the substantially line contact between the diamond and the wheel, indicated at 27, is parallel to the direction of travel of the surface 15 at the diamond, as shown best in FIGS. 2 and 3. The diamond may be rotated in either direction.

Preferably the extending shank 25 of the diamond is preformed to a cylindrical, or substantially cylindrical, conformation, with a conical, or substantially conical, point 29 having an apex 30 on the axis 12 which constitutes the central axis of the shank and point. If the point 29 is originally conical, and has one element of its cone parallel to the tangent of the wheel where contacted by the diamond, the wheel will soon generate the point 29 to establish substantially line contact between the diamond point and the wheel. Thereafter as the diamond wears, the conformation of the point 29 will remain substantially the same, as indicated by dotted lines at 31, and, since the shank is substantially cylindrical, the extent of the line contact between the diamond and the wheel will not be significantly increased so that the action of the diamond on the wheel will not change. Although the sides of the point 29 will be slightly curved, the point will remain substantially conical.

25 The tool 10 may be mounted in any conventional dressing or truing mechanism for movement, in either direction, across the surface to be operated on in the same manner as a conventional dressing or truing diamond.

30 By way of example the tool 10 may be mounted in the tool holder shown and described in U.S. Patent 2,565,687 for movement in translation across an arcuately contoured wheel 32 under the control of a cam, the spindle 11 thereby being moved parallel to the surface of the wheel in closely spaced relation thereto with the diamond 35 in engagement with the workpiece engaging periphery 33 of the wheel. As shown in FIG. 6, the slide unit 36 is mounted on the base unit 37 which has formed therein cylinder chamber 38. Chamber 38 receives a piston 39 with a rod 40 coupled to slide 36 for transverse actuation thereof. A truing tool slide housing 41 is slidably received in slide 36 and receives truing tool holder 42 in which the tool 10 is mounted. The traversing direction is perpendicular to the direction of movement of the wheel surface at the diamond and, in truing an arcuately contoured wheel such as wheel 32 in translation, the most precise truing is obtained when the substantially line contact between the diamond and the tool 45 is parallel to the direction of movement of the wheel surface at the diamond, and hence perpendicular to the traversing direction. It should be noted that when forming a contour having two slopes, such as 33 and 34, oriented at different angles to a traversing diamond as it moves across the wheel in translation, wear on one

50 side of a nonrotating diamond point by contact with one slope is likely to be significantly greater than wear on the other side of the diamond point by contact with the other slope because of the crystal orientation in the diamond, and the shaping, or truing, ability of the diamond rapidly deteriorates. Moreover, with the conventional nonrotating diamond, as a facet is worn on the diamond, one side of the facet will shape slope 33 and the other side of the facet will shape slope 34, impairing the precision of the truing operation as the span of the facet increases in the traversing direction. However, with a 55 rotating diamond oriented to establish substantially line contact with the wheel perpendicular to the traversing direction, the shape of the diamond is maintained and the span of the diamond where it contacts the wheel is

60 rapidly deteriorates. Moreover, with a rotating diamond oriented to establish substantially line contact with the wheel perpendicular to the traversing direction, the shape of the diamond is maintained and the span of the diamond where it contacts the wheel is quite small in the traversing direction. This span does not increase as the diamond wears and the ability of the diamond to produce precise truing does not diminish as the diamond wears.

In operation, the speed at which the wheel to be 65 dressed or trued is rotated, and the rate at which the

tool is traversed, or moved across the wheel, may be the same as used in conventional diamond truing and dressing. Any rotation of the diamond during the traverse of the wheel will prolong the life of the diamond by continuously changing the region of the diamond in contact with the wheel to facilitate continuous dissipation of generated heat. For better truing and dressing of the wheel, high speed rotation of the diamond is desirable. In a typical truing and dressing operation, a wheel having, for example, an initial diameter of 20 inches may be rotated at approximately 1250 revolutions per minute to give an initial surface speed of about 6500 feet per minute, and the diamond may be traversed at a conventional rate of .0015 inch per revolution of the wheel. The diamond which may, for example, have a diameter on the order of one-sixteenth of an inch at the base of the conical point, can be rotated at about 1600 revolutions per minute, and the axis of the diamond inclined 30 degrees from a line between the diamond and the axis of the wheel at a trailing angle.

What is claimed is:

1. The method of truing and dressing an abrasive wheel comprising the steps of rotating the abrasive wheel, rotatably driving a substantially conical shaped diamond point about a central axis through the apex of the conical point independently of the rotating abrasive wheel, and moving the rotatably driven diamond point across the wheel with the side of the conical point continuously in substantially line engagement with a moving surface of the rotating abrasive wheel, said diamond point moved at a trailing angle relative to the direction of movement of said surface with the line of engagement parallel to the direction of movement of said surface.

2. The method of truing and dressing a grinding wheel having a workpiece engaging surface comprising the steps of rotatably driving the grinding wheel, rotating a substantially conical shaped diamond point about a central axis through the apex of the conical point of the diamond independently of the grinding wheel and at a substantially constant angular speed, and moving the rotatably driven diamond point across the wheel in a traversing direction perpendicular to the direction of movement of the workpiece engaging surface at the diamond with the side of the conical point continuously contacting the workpiece engaging surface along a line parallel to the direction of movement of the workpiece engaging surface at the diamond and with the diamond point at a trailing angle relative to said direction of movement of the workpiece engaging surface.

3. The method of truing and dressing a grinding wheel having a workpiece engaging surface comprising the steps of rotating the grinding wheel at a predetermined angular speed, rotatably driving a substantially conical shaped diamond point about a central axis through the apex of the conical point of the diamond independently of the grinding wheel and at a constant angular speed at least as great as the angular speed of the grinding wheel, and moving the rotatably driven diamond point across the wheel for traversing perpendicular to the direction of movement of the workpiece engaging surface at the diamond with the side of the conical point continuously in substantially line contact with the workpiece engaging surface of the wheel, said diamond point moved at a trailing angle relative to the direction of movement of said surface with the line of engagement parallel to the direction of movement of said surface.

4. In a machine tool having a rotatable abrasive wheel, a mechanism for truing and dressing said wheel comprising a spindle having a longitudinal axis, a diamond having a substantially conical point carried at one end of the spindle with an apex on said axis, means to mount the spindle with the conical diamond point positioned for line engagement with the surface of the wheel to be operated on, a drive connected to the spindle to continuously rotate the spindle about its longitudinal axis for

rotation of the diamond, and means to move the spindle across the rotating wheel with the rotating diamond engaged with the surface of the wheel to be operated on at a trailing angle relative to the direction of movement of said wheel surface and with the line of engagement between the diamond point and the wheel parallel to said direction of movement of the wheel surface.

5. In a machine tool having a rotatable grinding wheel with a workpiece engaging surface, a mechanism for truing and dressing said surface comprising a housing, means to traverse the housing across said workpiece engaging surface in spaced relation thereto, a spindle having a longitudinal axis and having a diamond at one end terminating in a preformed conical point with an apex on said longitudinal axis, means to mount the spindle in the housing for rotation about said longitudinal axis, said spindle projecting from the housing for engagement of the diamond point with the workpiece engaging surface of the rotating wheel as the housing moves across said surface with the side of the conical point contacting with said wheel surface along a line parallel to the direction of motion of the wheel surface at the diamond and perpendicular to the traversing direction with the longitudinal axis at a trailing angle relative to the direction of motion of said surface at the diamond, and a drive operatively connected to the spindle to continuously rotate said spindle for rotation of the diamond as the housing is traversed across the wheel.

6. In a machine tool having a rotatable grinding wheel with a workpiece engaging surface, a mechanism for truing and dressing said surface comprising a spindle having a longitudinal axis, a diamond mounted at one end of the spindle with a substantially cylindrical extending shank terminating in a preformed conical point with an apex on said longitudinal axis, means to move the spindle across said workpiece engaging surface parallel thereto with the side of the diamond point in contact with said surface of the rotating wheel along a contact line parallel to the direction of motion of said surface at the diamond point and perpendicular to the direction of traversing movement with the diamond point at a trailing angle relative to said moving surface, and a drive operatively connected to the spindle to rotate said spindle at a substantially constant angular speed for rotation of said diamond continuously during engagement of the diamond with the wheel.

7. In a machine tool having a rotatable abrasive wheel, a mechanism for truing and dressing said wheel comprising a housing, a spindle having a longitudinal axis mounted in said housing for rotation about said axis, a diamond carried at one end of the spindle on said axis, means defining a chamber in the housing, a plurality of radially extending blades on the spindle and received in said chamber, means to circulate fluid through said chamber to rotate the blades and thereby rotate the spindle about said axis, and means to move the housing across the wheel with the axis of the spindle inclined at an angle relative to the surface to be operated on and with the rotating diamond engaged with said surface of the rotating wheel.

8. In a machine tool having a rotatable grinding wheel with a workpiece engaging surface, a mechanism for truing and dressing said surface comprising a housing, means to move the housing across said workpiece engaging surface in spaced relation therewith and parallel thereto, a spindle having a diamond mounted at one end with a substantially cylindrical extending shank terminating in a preformed conical point with an apex on said longitudinal axis, means to rotatably mount the spindle in the housing for engagement of the diamond point with the workpiece engaging surface of the wheel as the housing moves across said surface with the side of the conical point in substantially line contact with said wheel surface and with the longitudinal axis at a trailing angle relative to the direction of motion surface at the diamond,

means defining a chamber in the housing, means defining a plurality of turbine blades on the spindle in the housing, and means to circulate a driving medium through said chamber to rotate the spindle.

9. The method of truing and dressing a grinding wheel having a workpiece engaging surface comprising the steps of rotating the grinding wheel at a predetermined speed, rotatably driving a substantially conical shaped diamond point about a central axis through the apex of the conical point of the diamond independently of the rotating grinding wheel and at an angular speed greater than the angular speed of the grinding wheel, and moving the rotatably driven diamond point across the wheel for traversing perpendicular to the direction of movement of said surface at the diamond with the side of the conical point contacting the workpiece engaging surface of the wheel along a line parallel to the direction of movement of said surface at the diamond and with the diamond point at a trailing angle relative to said direction of movement of said surface.

10. The method of truing a grinding wheel having an arcuate workpiece engaging surface comprising the steps of rotatably driving the grinding wheel at a predetermined speed,

8
mined speed, rotating a substantially conical shaped diamond point about a central axis through the apex of the conical point of the diamond independently of the grinding wheel and at an angular speed at least as great as the angular speed of the grinding wheel, and traversing the rotatably driven diamond point across the wheel in translation with the side of the conical point contacting the workpiece engaging surface of the wheel along a line parallel to the direction of movement of said surface at the diamond and perpendicular to the traversing direction with the diamond point at a trailing angle relative to said direction of surface movement.
